UNITED STATES PATENT OFFICE.

WILLIAM HENRY NICKERSON, OF BROOKLINE, MASSACHUSETTS.

FOOT BEARING FOR SHOES.

Application filed January 13, 1926. Serial No. 81,075.

This invention relates to that portion of a shoe which provides a bearing surface for the bottom of the wearer's foot, and includes an insole which may be incorporated in the 5 shoe as a fixed part thereof, or may be inserted in a completed shoe and rest on the usual insole.

The invention is embodied in a foot bearing which includes an insole, and a molded 10 longitudinal arch supporter, preferably of steel, interposed between two layers formed by splitting the insole edgewise from its heel end through its shank portion. The split insole includes a bottom layer and a top 15 layer, each integral with the fore part of the sole, said layers providing a pocket for the reception of the arch supporter. The top layer is flexible so that it is adapted to be conformed accurately by pressure of the foot 20 upon it to the contour of the molded arch supporter, and to conform also to a resiliently compressible supplemental supporter for the metatarsal arch engaged with the forward end of the longitudinal supporter. The 25 top layer is also displaceable so that differently formed arch supporters may be used interchangeably, or in other words, in case an arch supporter of a given contour is unsatisfactory, another of a different contour 30 may be substituted therefor.

Of the accompanying drawings forming a part of this specification,

Figure 1 is a top plan view of a foot bearing embodying the invention, the top layer 35 being displaced and its free heel end portion broken away.

Figure 2 is a section on line 2—2 of Figure 1, showing the top member in its operative position.

40 Figures 3 and 4 are top views of two differently formed longitudinal arch supporters.

Figure 5 is a section on line 5—5 of Figure 3.

45 Figure 6 is a section on line 6—6 of Figure 4.

Figure 7 is a section on line 7—7 of Figure 3.

50 Figure 8 is a section on line 8—8 of Figure 4.

Figure 9 shows the split insole in longitudinal section and by full lines, the top layer being displaced and component parts of the shoe being shown by dotted lines.

55 Figure 10 is a view similar to Figure 9, showing also the longitudinal arch supporter

without the metatarsal supporter, the top layer being in its operative position.

The same reference characters indicate the same parts in all of the figures.

In carrying out my invention, I divide or split a full length insole edgewise from its heel end through its shank portion to form a bottom layer 12, a displaceable top layer 13, and an undivided fore part 14 with which the layers 12 and 13 are integral. Each layer includes a heel portion and a shank portion. 60 65 15 designates a molded longitudinal arch supporter, preferably of sheet steel, interposed between the layers and coextensive 70 lengthwise with the shank portions thereof. The top layer 13 covers the supporter 15, and is relatively thin and flexible so that it is adapted to be accurately conformed by the wearer's foot to the contour of the supporter. 75 Said contour may vary as indicated by the drawing, and its longitudinal curvature may be such that its midlength portion may be separated by a space 17 from the midlength portion of the bottom layer as shown by Figure 10.

I engage with the forward end of the longitudinal supporter, a supplemental supporter 18 for the metatarsal arch. The supporter 18 is of resiliently compressible material, such as soft vulcanized rubber or ordinary sponge rubber, and is preferably provided with convex top and bottom sides, the margin of the supporter being preferably oval as shown by Figure 1. The rear end of the supporter 18 may be provided with a slit adapted to receive the forward end of the longitudinal supporter 15 as shown by Figure 2.

The forward portion of the top layer 13 conforms to the supplemental supporter 18 as shown by Figure 2.

The bottom layer 12 is preferably considerably thicker than the top layer 13, so that the bottom layer may be attached to a component part or parts of the shoe, some of said parts being shown by dotted lines in Figures 9 and 10. The top layer 13 is displaceable as indicated by Figure 9, to permit the insertion of the arch supporter 15 or the two supporters 15 and 18 between the layers. The top layer may be releasably secured in its operative position to the bottom layer by any suitable means, such as cement, so that it may be displaced to permit the removal of a previously inserted arch supporter and the substitution of a differently 100 105 110 115

formed supporter therefor. The rear end of the longitudinal supporter 15 is considerably in advance of the rear ends of the sole layers as indicated by Figure 1, so that the heel ends of the layers may be connected by cement. The longitudinal supporter 15 may be secured at one or both ends to the bottom layer 12, by any suitable means, such as nails or rivets 19, engaged with the supporter, 10 passing through holes 20 therein, and engaged with the bottom layer.

I do not claim in this application the subject-matter illustrated by Figure 10, said subject-matter being claimed in another application filed by me May 27, 1927, Serial No. 15 194,678 entitled "Improvement in foot bearings for shoes."

I claim:

A foot bearing for shoes comprising an insole divided or split edgewise from its heel end through its shank portion to form a bottom layer, a displaceable top layer, and an undivided fore part, each layer including a heel and a shank portion; a molded longitudinal arch supporter interposed between the layers, and a resiliently compressible supplemental arch supporter engaged with the forward end of the longitudinal supporter and formed to support a metatarsal arch, the top layer covering and conforming to the two supporters.

In testimony whereof I have affixed my signature.

WILLIAM HENRY NICKERSON.
